Patented July 22, 1958

183,258

PORTABLE MAGNETIC DISC RECORDER OR SIMILAR ARTICLE

Paul E. King, New York, N. Y.

Application May 9, 1956, Serial No. 41,410

Term of patent 14 years

(Cl. D56—4)

Fig. 1

Fig. 2

Fig. 1 is a perspective view of a portable magnetic disc recorder or similar article, showing my new design from the front and in closed position, with the carrier handle extended; and

Fig. 2 is a perspective view similar to Fig. 1, but showing the same half open and with the handle in position close against the side wall.

The dominant features of my design reside in the portions shown in solid lines in the drawing. The stippling denotes the color black.

I claim:

The ornamental design for a portable magnetic disc recorder or similar article, as shown and described.
